CLAIM

I claim the ornamental design for a sandal, as shown and described.

DESCRIPTION

FIG. 1 is a left foot perspective view of a sandal, showing my new design.

FIG. 2 is a perspective outer edge view thereof;

FIG. 3 is a perspective inner edge view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines shown in the drawing disclosure are for illustrative purposes only and form no part of the claimed design.
